SHEET FEEDING MECHANISM

Filed April 11, 1925.

UNITED STATES PATENT OFFICE.

JOHN H. SHIPLEY, OF CLEVELAND, OHIO, ASSIGNOR TO THE CLEVELAND FOLDING MACHINE COMPANY, OF CLEVELAND, OHIO, A CORPORATION OF OHIO.

SHEET-FEEDING MECHANISM.

Application filed April 11, 1925. Serial No. 22,316.

My invention relates to improvements in sheet feeding mechanism and, more particularly, to adjuncts therefor, whereby the air blast utilized for assisting in the feeding of the sheets may be better applied and controlled, which is the prime object of said invention.

It is well known in this art that the application of air currents at the sides and edges of the sheets materially facilitates the operation of sheet feeding mechanism and various appliances have been devised for this purpose. My instant invention seeks to combine in the simplest and most reliable apparatus, suitable means for initiating successively, the contact of the topmost sheet with the sheet feeding member, and for reducing the friction of said sheet as it is withdrawn from the pile or stack. Said means are provided with adjustments whereby the air blast may be applied at different heights and may be varied in volume and directed in the most advantageous manner to correspond with the particular class of paper stock being handled at any given time.

The features and advantages of my improvement may well be explained in connection with the accompanying drawings, illustrating sufficient features of a sheet feeding mechanism to enable me fully to point out the particular construction embodying my invention, wherein:

Figure 1 is a fragmentary view in longitudinal section, illustrating a so-called pile-feeder, incorporating my improvements.

Fig. 2 is another fragmentary view in irregular transverse section on line 2—2, Fig. 1, which is sectionally broken away in parts.

Fig. 3 is an enlarged fragmentary section of the main air blast support.

Fig. 4 is a fragmentary view in front elevation, illustrating one type of vented air blast head, and

Fig. 5 is a similar view, illustrating a modified form thereof.

Throughout the several figures of the drawings, I have employed the same character of reference to indicate similar parts.

It will be recognized that the essentials of a pile-feeder adapted to feed sheets of paper from a stack upon the roller transfer table at the left are disclosed in Fig. 1

and the companion sectional view, Fig. 2. 55 Therein the rotary suction head *a* is positioned directly above the forward edges of the pile of sheets *b*, which are carried upon the vertically movable supporting table *c*, while the two initial rolls *d*, *d* of a roller 60 transfer table are indicated sectionally upon the left, toward which the sheets are successively advanced.

An air blast is applied at the front of the pile of sheets, supplied from a flexible pipe *e*, connecting with the upright *e'* and supporting a perforated T-head *f*, rotatably mounted in the transverse connection *f'*. The vented pipe *f* is provided with clips *f''*, adapted to be adjustably positioned over the 70 perforations *f'''* as required, while the pipe as a whole may be rotated within its connection *f'* by means of the lever arm *f''*. The details are best shown in the broken away portions of Fig. 2 and the fragmentary view, Fig. 4. 75

A modified form of the vented T-head is fragmentarily shown in Fig. 5 wherein the pipe *f* is provided, instead, with longitudinal slits *g*, disposed in alinement, which are 80 adapted to be entirely or partially covered by the corresponding spring metal clips *g'*. The ends of the pipe *f*, of course, are closed and the vented openings are spaced at suitable intervals better to adapt the same for 85 use with sheets of varying sizes.

Referring to the lower left hand portion of Fig. 1, it will be seen that the pipe *e'* is vertically adjustable within its sleeve support *e''*, wherein it is adapted to be held 90 by means of the screw *e'''*. Moreover, said sleeve support is longitudinally and axially adjustable along and upon the transverse rod *h*, being held in its adjustable positions by means of a thumb screw *h'*. These right-angle adjustments permit the approach and withdrawal of the blast pipe toward and from the sheets, as well as its vertical positioning with respect to the uppermost sheet, so that the air blast may be applied at the 100 most advantageous angle for lifting the topmost sheet, as *b'*, into contact with the rotary suction head *a*, and for distributing the air intermediately between said topmost sheet and the supporting sheet next below 105 it, in order to facilitate the successive feeding of the sheets.

It may be remarked that it is of consid-

erable importance not only to vary the height and direction of the air blast in an appliance of this class, but also to modify the volume and amount of the air discharged intermediately of the upper sheets, dependent upon the character of the particular paper stock that is being fed and the size and weight of the sheets. Preferably the air currents are directed against the upper edges of the sheets approximately in a horizontal plane, and from varying distances in advance thereof, hence, in addition to close regulation of the air currents, it is highly desirable to adjust the jet-producing means both horizontally and vertically with respect to the diminishing stack of sheets. Therefore, my instant appliance permits of the widest variation in the employment of an air blast in order to improve the operation of any sheet feeding mechanism dependent thereon for its better operation.

In the structure exemplifying my improvements, it will be seen that the darts indicate an intermediate or vertical positioning of the air blast pipe and head with a rotation of the vents so as to direct the air at a very wide angle against the edge of, and beneath the under face of sheet b' . Thus, the sheet is blown into contact with the under face of the rotary suction head a and it is directed by the rods a' as it is advanced between the contacting rolls i, i' to the roller transfer table d, d' .

An attendant very readily learns by making a few experimental adjustments of the height and inclination of the air blast pipe and the covering or uncovering of more or less of the vents therein, the manner in which he may best apply the air to any given size and weight of sheets that are desired to be fed in the machine from time

to time, particularly as all of the adjustments are simple and direct.

It will be understood that my invention may be embodied in various forms and may be applied to different sheet feeding mechanisms inasmuch as a typical use thereof alone is adopted in the foregoing description and accompanying drawings.

Having now described a typical embodiment of my improvements, I claim as new, and desire to secure by Letters Patent, in association with any suitable sheet feeding mechanism, the following:

1. In apparatus of the class described, the combination with sheet feeding means, of an associated air blast member positioned in advance thereof, and a mounting therefor, permitting its vertical and horizontal adjustment with respect to said sheet feeding means, substantially as set forth.

2. In apparatus of the class described, the combination with a rotatable suction head, of an associated air blast head positioned relatively in advance thereof, means for controlling the direction of the air blast, and additional means for adjusting it both horizontally and vertically with respect to said rotatable suction head, substantially as set forth.

3. In apparatus of the class described, the combination with a rotatable suction head, of a co-acting vented air blast head positioned relatively in advance thereof, means for adjusting its angular position and a mounting permitting the vertical and horizontal adjustment of said air blast head, substantially as set forth.

In testimony whereof I do now affix my signature.

JOHN H. SHIPLEY.
